The ornamental design for a pool air pillow as shown and described.

DESCRIPTION

FIG. 1 is a perspective view of a pool air pillow showing my new design;

FIG. 2 is another perspective view thereof;

FIG. 3 is another perspective view thereof;

FIG. 4 is a front view thereof;

FIG. 5 is a back view thereof;

FIG. 6 is a left view thereof;

FIG. 7 is a right view thereof;

FIG. 8 is a top plan view thereof; and,

FIG. 9 is a partial enlarged view of portion 9 in FIG. 1.

The broken lines depict portions of the pool air pillow and form no part of the claimed design. The dot-dash lines that demarcate claimed areas in FIGS. 1 & 9 have been included to show enlargement for clarity. The lines themselves do not form part of the claimed design.
